TUMBLER PULL TOY UNIT

James A. Brown, 10712 Lockridge Drive,
Silver Spring, Md.

Filed Oct. 9, 1962, Ser. No. 72,054

Term of patent 3½ years

(Cl. D34—15)

FIG. 1

I claim:

The ornamental design for a tumbler pull toy unit, as shown and described.
